UNITED STATES PATENT OFFICE.

EVERETT WORTHINGTON, OF CHICAGO, ILLINOIS, ASSIGNOR TO ZENITH RADIO CORPORATION, OF CHICAGO, ILLINOIS, A CORPORATION OF ILLINOIS.

DESIGN FOR A RADIOCABINET.

Application filed December 7, 1925. Serial No. 15,654. Term of patent 14 years.

To all whom it may concern:

Be it known that I, EVERETT WORTHINGTON, a citizen of the United States, residing at Chicago, in the county of Cook and State of Illinois, have invented a new, original, and ornamental Design for Radiocabinet, of which the following is a specification, reference being had to the accompanying drawing, forming part thereof.

In the drawing, Fig. 1 is a perspective view of the radio cabinet and Fig. 2 is a plan view, on a smaller scale.

I claim:

The ornamental design for a radiocabinet, as shown.

EVERETT WORTHINGTON.
